US0D1053514S

(12) **United States Design Patent** (10) **Patent No.:** **US D1,053,514 S**
(45) **Date of Patent:** **** Dec. 10, 2024**

(54) **SHOE**

(71) Applicant: **GOLDEN GOOSE S.p.A.**, Milan (IT)

(72) Inventor: **Marco Neroni**, Milan (IT)

(73) Assignee: **GOLDEN GOOSE S.p.A.**, Milan (IT)

(**) Term: **15 Years**

(21) Appl. No.: **29/905,663**

(22) Filed: **Oct. 24, 2023**

Related U.S. Application Data

(62) Division of application No. 35/513,254, filed on Dec. 2, 2021 (U.S. filing date under 35 U.S.C. 384), and having an international filing date of Dec. 2, 2021.

(30) **Foreign Application Priority Data**

Jun. 3, 2021 (IT) 4020211000001499

(51) **LOC (14) Cl.** **02-04**

(52) **U.S. Cl.**

USPC **D2/902; D2/944**

(58) **Field of Classification Search**

USPC D2/896, 902, 907-908, 916, 943-944,
D2/947, 969, 972-974

CPC A43B 23/025

See application file for complete search history.
